SEWING MACHINE

Max L. Waterman, Fairfield, Conn., assignor to
The Singer Manufacturing Company, Elizabeth, N. J., a corporation of New Jersey

Application September 13, 1939, Serial No. 294,615

6 Claims. (Cl. 112—258)

This invention relates to sewing machines more particularly of the small portable electrically driven type for family use.

The invention has for an object to provide a machine of this nature which is simple and inexpensive in construction, small in size and compact in the arrangement of its component parts, and which is quiet running and efficient in its operation.

Considerations such as weight, cost and housed-ability dictate the choice of a high-speed motor of small size for an electric sewing machine of the type in question and, as a result, the disposition of the motor and the construction of the machine to receive it, as well as the driving connections for transmitting the power of the high-speed motor to the moderate speed machine are problems which must be met and solved in a successful portable electric family type sewing machine.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the accompanying drawings, Fig. 1 is a longitudinal vertical section through a sewing machine embodying the invention. Figs. 2 and 3 are perspective views of the rotary hook element of the machine. Fig. 4 is a top plan view of the machine with the overhanging bracket-arm in longitudinal section. Fig. 5 is a right end elevation of the machine with the bracket-arm standard in vertical section. Fig. 6 is a transverse vertical sectional view through the machine-bed showing the reversible feed-mechanism. Fig. 7 is a detail view of a part of the take-up mechanism. Fig. 8 is a front end elevation of the machine with the bed in transverse vertical section. Fig. 9 is a top plan view of the rotary hook.

Fig. 10 is a top plan view of the stationary bobbin-case normally nested in the rotary hook of Fig. 9. Figs. 11 and 12 are perspective views of the thread-case of Fig. 10. Fig. 13 is a vertical sectional view through the hook axis in a plane at right angles to the plane of the bed-section of Fig. 8. Fig. 14 is a detail view of the bobbin-case rotation restraining device on the sewing machine throat-plate. Fig. 15 is a horizontal section through the machine-bed, below

the top or work-supporting surface thereof, showing the bottom closure for the bed and the motor mounting means carried by said bottom closure. Fig. 16 is a horizontal section through the machine-bed, looking upwardly, taken in the plane of the top surface of the bottom bed-closure plate or board, to show the under bed mechanism in bottom plan, and Fig. 17 is a plan view of the throat-plate of the machine.

10 The machine frame comprises a hollow box-type bed 1 with downturned side and end walls 2 and 3 and a top work-supporting wall into which is let the throat-plate 4. The bottom of the bed is closed by the bottom plate or board 5 which is secured to the bed 1 by screws 6 and rests on the rubber feet 7.

Secured to and rising from the bed 1 is the standard 8 of the overhanging bracket-arm 9 terminating in the head 10 which latter carries 20 the usual reciprocatory needle-bar 11 and spring-pressed presser-bar 12 for the needle 13 and presser-foot 14, respectively.

The main-shaft 15, which makes one revolution per stitch, is journaled in the bed 1 and has 25 an outboard projection 15' on which is mounted the combined belt-pulley and balance wheel 16. It will be observed that the end wall 3 of the bed adjacent the bracket-arm standard 8 is inset to provide an externally open frame pocket with 30 overhanging top and side aprons or guard-flanges 17, 18, Fig. 16, for the belt 19, the main-shaft pulley 16 and the motor-pulley 20.

The motor-pulley 20 is preferably not mounted directly on the motor-shaft 21 but is fixed 35 with the gear 22 to a sleeve 23 journaled on the stud-pin 24 carried by the motor-frame 25. The motor-shaft 21 has fixed to it a pinion 26 meshing with the gear 22 and driving the latter and the pulley 20 at a reduced speed, say one-third 40 the speed of the motor-shaft. The motor-pulley 20 may, in turn, be about one-half the pitch-diameter of the pulley 16, whereby a further reduction in speed is effected so that the main-shaft 15 of the machine is driven at about one-sixth motor speed. Any ratio may, of course, be selected within reasonable limits without departure from the invention. Adequate power 45 may thus be had in a small high-speed motor which may be easily housed within the bed cavity of a portable family machine of the type hereinabove indicated. Also the need for a large main-shaft pulley 16 is avoided. The pulley 16 is adequately guarded by the bed extensions 17, 18, without encroaching on the space above the

level of the work-supporting plane of the machine.

The motor 25 is preferably carried by a plate-like lever 27 which is fulcrumed at 28 on the baseboard 5 and has between its ends an upturned lip 29 which is engaged by the spring-pressed plunger 30 of the belt-tightener fitting 31 mounted on the baseboard 5. There is fulcrumed at 32 on an upturned lip 33 of the plate 27 a finger-lever 34 which extends through a slot 35 in the recessed or inset portion 2^a of the front side wall 2 of the bed 1 for access. This lever 34 has a laterally bent tongue 36 which is adapted to engage the rear side of the front wall 2 of the bed 1 and swing the motor-carrying lever 27 toward the main-shaft 15, or to dotted line position, Fig. 15, to loosen the belt 19 when the finger piece 34 is depressed from the position shown in Fig. 5. When in this position the motor and pulley 20 will run idly and may be used to wind bobbins received on the pulley hub-extension or spindle 20'.

The upper run of the belt is supported by the pin 37 so that, when the belt is slackened, it will not sag of its own weight and grip the motor pulley.

The needle-bar 11 is connected by the link 38 to the crank-arm 39 on the rock-shaft 40 in the bracket-arm 9. The rock-shaft 40 has fixed to it another crank-arm 41 which is actuated by the pitman 42 from the eccentric 43 on the main-shaft 15.

The needle-thread take-up arm 44 is fixed to the rock-shaft 45 in the bracket-arm 9 which rock-shaft has fixed to it a pin 46 slidably engaged by the cross-pin 47 pivoted in the upper forked end of the lever 48. The lever 48 embraces an eccentric 49 at its lower end and is formed between its ends with a slot 50 to slidably embrace the fulcrum block 51 on the pin 52 extending transversely of the standard 8. The described mechanism moves the cross-pin 47 in an elliptical path, shown in dotted lines in Fig. 5, and gives to the take-up a fast up-stroke or thread take-up motion and a slow down-stroke or slack giving motion as is commonly required of take-ups for rotary hook sewing machines such as the present machine. The present form of take-up is not herein claimed as it forms the subject of my copending application, Serial No. 291,839, filed August 25, 1939.

The rotary hook comprises a cup-shaped body 53 having a loop-taking beak 54 and a circular open topped raceway 55 in which rests the peripheral bearing rib 56 of the bobbin-case 57. The hook-body 53 is carried by the vertical hook-shaft 58 journaled in the bed 1 and having fixed to it a spiral gear 59 meshing 2 to 1 with the driving gear 60 on the main-shaft 15. Thus the hook is driven two revolutions for one revolution of the main-shaft.

The bobbin-case 57 is formed at one side with the rotation-restraining tongue 61 which enters a rotation-restraining notch between the two lugs 62 on the under side of the throat-plate 4.

The machine is preferably provided with a mechanical opener for forcibly oscillating the bobbin-case in a direction opposite to the direction of rotation of the hook-body 53, at the period of the cycle when the needle loop is being contracted by the take-up after having been cast about the bobbin-case by the rotary hook; the purpose being to open an escape gap for the contracting needle-loop between the rotation-restraining tongue 61 and one of the throat-plate 75

lugs 62. The mechanical opener may take the form of an eccentric operated vibratory lever 63 fulcrumed at 64 in the bed 1 and carrying the vertically adjustable tappet 65 adapted to periodically engage the shoulder 66 on the bobbin-case to open the needle-loop escape gap between the tongue 61 and shoulder 62 last passed by the rotary hook beak.

It will be observed that the bobbin-case 57 rests by gravity in the hook raceway and that the cover slide plate 67, Figs. 1 and 8, is disposed directly above the bobbin-case 57 and holds the latter against accidental displacement from its properly nested relation with the hook body. There is enough clearance between the bobbin-case and cover slide to permit free passage of the needle-thread loops about the bobbin-case; the cover slide 67 being cut away at its under side at 68, if necessary.

20 The feeding mechanism comprises the usual feed-dog 69 which is carried by the feed-bar 70 formed with a depending horizontally slotted portion 71 embracing the feed-lift cam 72 on the main-shaft 15. The feed-bar is pivotally connected at its rearward end to the supporting rocker-arm 73 which swings on the axis of the shaft 74 for the support of the feed-bar.

There is fulcrumed at 75 on the bed a rocking frame 76 which has a slotted portion 77 embracing the feed-eccentric 78 on the main-shaft. The frame 76 carries a cylindrical pin 79 slidably engaged by a cross-pin 80 in the forked end of a link 81 which is connected at its other end to an arm 73' rigid with the feed-rocker 73. The axes 30 of the fulcrum 75 and cylindrical pin 79 intersect and when the cross-pin 79 is shifted into axial coincidence with the fulcrum 75 the rocking motion of the frame 76 will impart no motion to the feed-rocker 73. When the link 81 occupies full line position, Fig. 6, or any position above the axis of the fulcrum 75 there will be a forward feed of the work, whereas, when the link 81 occupies dotted line position, Fig. 6, or any position below the axis of the fulcrum 75 there will be a reverse feed of the work, as will be readily understood by those skilled in the art. The link 81 is connected by a link 82 to a feed-regulating lever 83 which is fulcrumed at 84 within the bed 1 and has an accessible portion 85 projecting forwardly through a vertical slot 86 in the recessed portion 2^a of the front wall 2 of the bed. A friction washer 87, Fig. 16, at the fulcrum of the feed-regulating lever 83, holds such lever stationary in any selected position to which it may be shifted by the operator.

60 The bobbin 88 rests by gravity in the bobbin-cavity of the bobbin-case 57 which is formed at one side with a cutaway 89 to expose one flange of the bobbin and facilitate removal of the bobbin; the cutaway 89 functioning as a finger-clearance notch.

The belt 19, being accessible exteriorly of the box-type bed 1, is readily removable and replaceable, without disassembly of any of the machine parts, yet is adequately guarded and protected by the bed wall extensions 17, 18.

Having thus set forth the nature of the invention what I claim herein is:

1. A sewing machine having a frame formed with a box-type bed and an overhanging bracket-arm, said bed having one of its external walls inset to provide a wide open pocket, a main-shaft and an electric motor disposed in said bed, spaced motor and machine-pulleys in said pocket,

and a belt connection in said pocket between said pulleys.

2. A sewing machine having a frame including a box-type bed and overhanging bracket-arm, said bed having its external end wall adjacent the bracket-arm standard inset to provide a wide open end-pocket, a main-shaft journaled in said bed and having an outboard projection in said pocket, a main-shaft pulley in said pocket, an electric motor in said bed, a motor-pulley in said pocket, and a belt in said pocket connecting said motor and main-shaft pulleys.

3. A sewing machine having a frame including a box-type bed and overhanging bracket-arm, said bed having one of its external end walls inset to provide external top and side wall bed extensions beyond the plane of said inset external end wall, a shaft journaled in said bed and extending through said end wall, a pulley carried by said shaft exteriorly of said end wall, 20 a motor disposed in said bed, a motor pulley in the plane of said first mentioned pulley, and a belt connecting said pulleys and guarded by said bed wall extensions.

4. A sewing machine having a frame including a box-type bed with external top, bottom, side and end walls, an overhanging bracket-arm, one of said external bed end walls being inset from the adjacent ends of the top, bottom and side walls to form a wide open bed pocket, a main-shaft in said bed and having an outboard pro-

jection in said pocket, a pulley on said shaft in said pocket, said pulley being contained entirely between the planes of the top and bottom external walls of said bed, a motor in said bed, 5 a motor-pulley smaller than said first mentioned pulley, said motor-pulley being driven by said motor at a reduced speed and disposed in said pocket, and a belt in said pocket connecting the motor and machine-pulleys.

10 5. A sewing machine having a box-type bed with inset external front and end walls affording wide open front and end bed pockets, a main-shaft journaled in said bed a motor housed in said bed, motor and main-shaft pulleys and a driving belt in said open end bed pocket, and a lever connected to said motor and having a terminal portion accessible in said open front wall pocket for shifting the motor to slacken the driving belt.

15 6. A sewing machine having a frame including a box-type bed and overhanging bracket-arm, said bed having an inset external wall providing a wide open pocket, a main-shaft journaled in said bed and extending into said pocket, a 25 driving motor housed in said bed, and driving connections between said motor and main-shaft, said connections including driving and driven belt-pulleys and a driving belt disposed in said pocket.

30 MAX L. WATERMAN.
